UNITED STATES PATENT OFFICE

115,685

DESIGN FOR AN AUTOMOTIVE STEERING WHEEL

Oswald B. Carson, Scarsdale, N. Y., assignor to
American Hard Rubber Company, New York,
N. Y.

Application May 16, 1938, Serial No. 77,240

Term of patent 7 years

To all whom it may concern:

Be it known that I, Oswald B. Carson, a citizen of the United States and a resident of Scarsdale, in the county of Westchester and State of New York, have invented a new, original, and ornamental Design for Automotive Steering Wheel, of which the following is a specification, reference being had to the accompanying drawing, forming a part thereof, and in which:

Figure 1 is a plan view of an automotive steering wheel embodying my new design, a domi-

nant feature of my design being the particular conformation of the spokes;

Fig. 2 is a vertical sectional view along the line 2—2 of Fig. 1; and

Fig. 3 is a vertical sectional view along the line 3—3 of Fig. 1.

I claim:

The ornamental design for an automotive steering wheel, as shown and described.

OSWALD B. CARSON.
